UNITED STATES PATENT OFFICE.

WILLIAM A. CHRYSST, OF DAYTON, OHIO, ASSIGNOR TO THE DAYTON ENGINEERING LABORATORIES COMPANY, A CORPORATION OF OHIO.

ENGINE STARTING SYSTEM.

1,288,836.

Specification of Letters Patent. Patented Dec. 24, 1918.

Application filed May 29, 1914. Serial No. 840,761.

To all whom it may concern:

Be it known that I, WILLIAM A. CHRYSST, a citizen of the United States of America, residing at Dayton, county of Montgomery and State of Ohio, have invented certain new and useful Improvements in Engine Starting Systems, of which the following is a full, clear, and exact description.

This invention relates to starting devices 10 for combustion engines and more particularly to starting devices, wherein an electric motor is used for cranking a gas engine.

In devices of this character, where the electric motor normally stands disconnected 15 from the gas engine, it is customary to have some means of connecting the two, and these devices are so arranged that the electric motor is given an initial movement preliminary to its cranking movement, this initial 20 movement being for the purpose of facilitating the connection between the motor and the gas engine.

The present improvements relate to an arrangement of the electric circuits for 25 curing this preliminary or initial movement, with relation to the main starting or cranking movement. And in the particular form adopted herein, the electric motor is given a slow initial movement by utilizing an auxiliary field connection which gives a different field intensity from the field used for 30 the main cranking operation.

Further objects and advantages of the 35 present invention will appear from the following description, reference being had to the accompanying drawings, wherein a preferred form of one embodiment of the present invention is clearly shown.

In the drawings:

40 Figure 1 is a diagrammatic view of an electrical system embodying the present invention.

Fig. 2 is a fragmentary plan view of the starting unit, the shiftable transmission gear 45 and engine, the gear being shown in uncoupled position.

Fig. 3 is a detail fragmentary view of the arrangement of the shiftable transmission devise for co-operating with the driving 50 pinion of the motor and the gear wheel which operates relative to the crank shaft of the engine.

The present invention preferably com-

prises a dynamo electric machine, similar in certain of its parts to the structure set forth 55 in the co-pending applications, Serial No. 633,443, filed June 15, 1911, now Patent 1,150,523, Aug. 17, 1915, Serial No. 721,237, filed September 19, 1912, now Patent 1,240,348, Sept. 18, 1917, and Serial No. 60 789,641, filed September 18, 1913, now Patent 1,250,188, Dec. 18, 1917.

The devices shown in the applications just referred to, are what is known as the single unit type of machine, wherein the electric 65 machine acts as a motor to crank the engine and also as a generator to store power in the batteries. But, the present improvements have to do only with the motor operation of devices of this character, that is, the operation 70 of the electric machine acting as a motor to crank the engine, and as above explained, having arrangements to provide a preliminary or slow initial movement for the purpose of connecting or enmeshing the 75 electric motor with the engine.

While therefore these improvements are shown for convenience, particularly with the complete system referred to, it is to be understood that the inventions are applicable 80 to any form of motor starting device.

While the structure set forth in the co-pending applications is similar as regarding certain parts to that of the present invention, certain novel elements and combinations 85 of elements have been included in the present invention which are entirely apart from the applications mentioned above.

Referring to the drawing, and particularly to Fig. 1, the numeral 20 designates 90 any suitable accumulator or battery of a predetermined number of cells, and adapted to be connected to the electric machine, to operate the same as a motor, through the following circuit:

From the battery 20, through the wire 21, which in the present case is common both to the motor and generator circuits, to the common plate 22 of the controller switch.

When the machine is being employed as 100 a motor for starting purposes, the element 23 of the controller switch will be shifted into the position shown in dotted lines in Fig. 1, so that the current will travel across the switch to the plate 24, and thus to the 105 main series winding 25, via wire 26. From

the series winding it will pass through the wire 27, brush 28, armature 29, brush 30, back to the battery, via the wire 31.

The above clearly describes the circuit which is employed when the motor is used for starting purposes. The motor, however, is initially or normally disconnected from the engine, and it is therefore advisable to have some means for connecting the motor with the engine for starting purposes.

In one of the preferred forms of so connecting the engine and motor for starting purposes, a shiftable transmission or connecting device is employed, which comprises a pair of pinions 102 and 103 respectively, of different diameters, one of which is movable into engagement with the armature pinion 101, while the other will engage with the teeth 104 formed on or connected to the periphery of the flywheel.

It will sometimes occur that when the motor or transmission members are at rest, the teeth of the respective members will so conflict that it is impossible to shift the transmission gearing to couple up the engine and the motor, without first changing the relative position of the transmission pinions and the armature pinion.

The shifting of the movable element 23 of the controller switch is effected by the rod 106, which also controls the shifting of the transmission members 102 and 103, but the relative arrangement of the element 23 of the switch, and the transmission pinions is such that the shifting of the switch will not occur until a complete enmeshment of the pinions 102 and 103 has been effected with the armature pinion 101 and the flywheel teeth 104.

The inherent construction and arrangement of the motor in the present invention is adapted to facilitate the shifting of the transmission members to effectually couple up the motor to the engine for starting purposes, and comprises a supplemental series field winding 32, which is preferably included in the same field coil structure as the series winding 25.

This supplemental series field winding is of higher resistance than the main series winding 25, so that at such times as the motor is operated under the effect of this supplemental series winding alone, the torque and speed of the motor will be reduced as compared to the ordinary torque and speed effect of the motor, when operating for starting purposes.

This winding 32, as is clearly shown in Fig. 1 is preferably connected in parallel with the main series winding 25, at such times as the shiftable element 23 of the switch is in its dotted line position, so as to close a supplemental circuit through the contact 24^a.

By referring to Fig. 1, it will be seen

that the contact element 24^a is connected with the conductor 24^b, which in turn is connected to the wire or conductor 37 on the battery side of the supplemental coil or winding 32. Now, as the switch element 23 is moved to dotted line position, the current will not only flow from the common switch plate 22 to the motor plate 24 and thence through the main series winding 25 to the armature 29, but a certain amount of current will also pass through the conductor 24^b, wire 37, supplemental coil 32, thence to the armature 29, via the conductor 27. In this construction, it will be seen that the supplemental winding 32 is in parallel with the main series winding 25, with regard to the common armature 29. This construction and arrangement of the windings will give an accumulative effect when the machine is operating as a motor and will tend to increase the torque effect of the motor, thus increasing the efficiency thereof as a cranking device.

However, when the controller element 33, which in the present instance is shown as a push button, is operated to close the contacts 35 and 36, a circuit will be closed from the battery 20, through the wire 21, branch wires 34, contact plates 35 and 36 respectively, branch wire 37, winding 32, to the brush 28, via wire 27, across the armature 29, through brush 30, back to the battery, via wire 31.

This circuit will shunt around the main series winding 25, so that the series winding 32 will constitute the only series winding of the motor, and thus will result in the motor operating at a reduced speed, and with a reduced torque effect, because of the relative high resistance of this winding, as compared with the resistance of the main series winding.

This movement of the armature of the motor at a slow initial speed and with slight torque effect, constantly changes the relative positions between the teeth of the pinion 102 and the teeth of the armature pinion 101, so that as soon as any pressure is applied to the rod 106, in an attempt to pull the transmission pinion into engagement with the motor and with the engine, this engagement will be readily effected, inasmuch as the conflict between the faces of the teeth on the pinion 102 with those on the pinion 101 will be entirely eliminated at least to all practical purposes.

It will further be seen that by having the supplemental series winding 32 connected in parallel with the main winding 25, during the actual starting operation of the motor, an accumulative effect will result. That is, although the supplemental winding 32 is of higher resistance than the winding 25, there will be a certain amount of current which will pass through this winding, which

will, of course, tend to create a field of its own, and this field will simply be in accumulation with the field created by current passing through the main series winding 25.

5 The accompanying drawing illustrates one form of the present invention, but it will be obvious that a variety of other forms may be employed to secure the desired result; that is, to provide for the initial operation of the motor, so that the speed and torque effect thereof will be materially reduced, as compared with the speed and torque effect of the motor, during the actual starting operation. However, it is not 10 thought necessary to illustrate and describe the variety of forms of the present invention for accomplishing the desired results.

In Fig. 1 there has been shown diagrammatically the electrical connections for the 20 machine, when it is employed as a generator.

The generator 50 is preferably of the shunt wound type and comprises the field winding 51. The voltage of the generator is preferably controlled by means of a regulator 52, which may be of the type shown in 25 the co-pending application, Serial No. 714,234, filed August 9, 1912. A cutout device 53 is also provided, to prevent the battery from charging back through the generator and operating the same as a motor, at such times as the voltage of the battery becomes greater than the voltage of the generator, or at such times as the generator is at 30 rest and the battery is partly charged. This 35 cutout relay device has been fully described and shown in connection with the co-pending application, Serial No. 721,237, filed September 19, 1912, now Patent 1,240,348, Sept. 18, 1917.

40 Of course, when the electric machine combines both the function of a motor and generator, it is necessary to provide some drive from the engine to the generator, in order to operate the same, and in this case, such 45 as is clearly shown in the co-pending application, Serial No. 721,237, filed September 19, 1912, suitable clutch mechanism will be provided to permit the machine to be run as a motor, free from connection with the engine, which is necessary to operate the machine as a motor.

In Fig. 2 of the drawing, a drive similar to that described in the co-pending application referred to above is clearly shown, 55 wherein connection is made with the timing gears so as to drive the shaft 107 at substantially engine speed. The clutch mechanism referred to above may be of any suitable type and is inclosed in the casing 108, and is 60 so arranged that when the electric machine is operating as a motor, a relative movement will be possible between the shaft 107 and the armature shaft.

By referring to Fig. 3, a fragmentary 65 tail view of the starting gearing is clearly

shown. The armature pinion 101 is shown as being emmeshed with the pinion 102, while the pinion 103 of the shiftable mechanism is engaged with the teeth formed on the periphery of the flywheel.

70 It will sometimes happen that the engine will become self-operating while the above described gearing is still in mesh, and in this case, of course, would rotate the armature at an extremely high speed.

75 In order to prevent this, a friction clutch 109 may be provided between the elements 102 and 103, so as to permit the flywheel 105 and the pinion 103 to run ahead of the pinion 102, and the armature pinion 101, at 80 such times as the speed of the engine becomes greater than the speed of the motor.

85 While the form of mechanism herein described constitutes a preferred form of embodiment of the invention, it is to be understood that other forms may be adopted, all coming within the scope of the claims which follow.

What I claim is as follows:

1. In a starting device for engines, the 90 combination with an electric machine operable as a motor and having a main series winding operable to effect a field of high intensity, to be used for starting purposes, and a supplemental series field winding operable to effect a field of low intensity, to be used for imparting a slow initial operation to the electric machine; of an accumulator; circuit connections between the accumulator and the windings of the electric 95 machine; shiftable connections between the engine and electric machine; and means for initially closing the motor circuit through the supplemental field winding only to give 100 a low intensity field, and subsequently for 105 shifting said shiftable connections into engagement and for closing the motor circuit through the main winding to give a field of high intensity.

2. In a starting device for engines, the 110 combination with an electric motor, comprising a pair of series field windings of different resistances; of an engine; normally disconnected means operable to couple up the motor and engine for starting purposes; a 115 current source; means for initially connecting said source with the series winding of greater resistance only, whereby to operate the motor initially with a reduced torque effect to facilitate connecting up of the engine and the motor; and means for connecting the coupling means and for connecting the current source with the series winding of less resistance, whereby to operate the motor to crank the engine.

120 3. In a starting device for engines the combination with an electric motor including a plurality of series field windings and a common armature winding; means for connecting the engine and motor together for 125 130

starting purposes; a source of current; circuit connections between the source of current and the motor windings; and means for initially closing the circuit connections through one of said series windings and the armature winding to facilitate the connection of the motor to the engine; and means for controlling the connecting means and for connecting the source of current and said

series windings in parallel, and together in 10 series with the armature winding for operating the motor for starting purposes.

In testimony whereof I affix my signature in the presence of two subscribing witnesses.
